UNITED STATES PATENT OFFICE.

GEORGE A. JOHNSON, OF CHICAGO, ILLINOIS, ASSIGNOR TO WILLIAM H. MINER, OF CHICAGO, ILLINOIS.

DRAFT-YOKE FOR RAILWAY-CAR DRAFT-RIGGING.

1,112,703.

Specification of Letters Patent.

Patented Oct. 6, 1914.

Application filed February 21, 1913. Serial No. 749,913.

To all whom it may concern:

Be it known that I, GEORGE A. JOHNSON, a citizen of the United States, residing at Chicago, in the county of Cook and State 5 of Illinois, have invented a certain new and useful Improvement in Draft-Yokes for Railway-Car Draft-Rigging, of which the following is a full, clear, concise, and exact description, reference being had to the accompanying drawings, forming a part of this specification.

My invention relates to improvements in draft yokes for railway car draft rigging.

One object of my invention is to provide 15 a draft yoke, which while performing its usual function as a yoke may serve as a draw bar extension, and one capable of employment with the standard draw bar.

A further object is to provide a draft yoke 20 adapted to forwardly extend the standard draw bar without change of stop members or the location of same, and without change of other parts of the draft rigging.

In the drawings forming a part of this 25 specification Figure 1 is a side elevation of a draft rigging for railway cars embodying my invention. Fig. 2 is a plan view showing the parts in normal position. Fig. 3 is a plan view showing the position of parts 30 in extreme forward movement of the draw bar. Fig. 4 is a cross sectional view on line 4-4 of Fig. 3. Fig. 5 is an enlarged detail showing in perspective the thimble. Fig. 7 is a plan view showing the position 35 of parts in full compressing movement. Fig. 6 is an enlarged view of a modification in the thimble.

Referring to the drawings 8, 8 represent 40 draft sills or parts of the car frame to which the draft rigging is attached, 9 the end sills, 10 the buffer block, 11 the draw bar carry iron, 12, 12 stop members provided with the front stop shoulders 13, 13 and rear stop shoulders 14, 14, front limiting 45 stop shoulders 15, 15 and rear limiting stop shoulders 16, 16, 17 the draw bar of standard type, 18, 18 tie plates suitably secured to the draft sills; all the foregoing parts being of well known construction.

The numeral 19 represents the draft yoke 50 having the upper and lower limbs 20 and 21 respectively, the forward ends of which 22 are forwardly extended beyond the front stop shoulders, and engage the hollow yoke head 23, which by means of the longitudi-

nally extended slot 24 therein and the coupler key 25 pass therethrough and through the transverse opening 26 in the draw bar 17, and is in sliding engagement with the said draw bar.

The numeral 27 represents a draft gear or compression resisting member, which with the front and rear followers 28 and 29 respectively are disposed in the lateral opening 30 of the draft yoke 19. The thimble 31 comprises upper and lower horizontal plates 32 and 33 respectively, each provided with a longitudinal slot 34 adapted for the passage of a limb of the draft yoke there-through, and front and rear vertical transverse plates 35 and 36 respectively securing the plates 32 and 33 to each other, and preferably integral with the same and the central connecting web 37.

The longitudinal grooves 34, 34 are preferably provided with longitudinally disposed ribs 38, 38 to adapt them for easy sliding movement upon the limbs of the draft yoke. The thimble 31 is placed on said draft yoke back of the head 23 and in front of the front follower 28. On forward movement of the draw bar the thimble 31 is in loose engagement with the limbs of the yoke, and on rearward movement of the draw bar the rear end of said draw bar engages the forward plate 35 of the said thimble while the rear plate 36 of said thimble engages the front follower 28, and while the draw bar moves rearwardly through the head 23 of the draft yoke the coupler key slides rearwardly in the slots 24 in the said head, the draw bar being in direct engagement in buffing movement with the slidable thimble 31.

Fig. 6 illustrates a modification of the thimble, the same being provided on its upper and lower faces with a longitudinal groove 39, the sides of which are formed by the shoulders 39, 39, the said grooves being each adapted to receive a limb of the draft yoke therein. In the modification the thimble is preferably made of two parts 40 and 41, and preferably engaging each other by tongue and groove engagement, as illustrated at the numeral 42, the members 40 and 41 being adapted for insertion at either side of the draft yoke into the lateral opening 30 of said yoke; and being provided with means, preferably bolts or rivets 43, securing them together.

I claim:—

1. In a draft rigging, the combination of a draw bar with a draft yoke and a thimble, the said thimble being in sliding engagement with the draft yoke and adapted to engage the draw bar, the said thimble comprising a block provided with longitudinal slots for the passage of the limbs of the draft yoke.
2. In a draft rigging, the combination with a draw bar, draft gear and draft yoke, of a thimble, said thimble being interposed between the draw bar and draft gear, and slidably engaging the draft yoke.

GEORGE A. JOHNSON.
